UNITED STATES PATENT OFFICE.

CLINTON BROWNING, OF ALLEGHENY CITY, PENNSYLVANIA, ASSIGNOR OF
THREE-EIGHTHS TO LINDSAY & McCUTCHEON, OF SAME PLACE.

CAR-COUPING.

SPECIFICATION forming part of Letters Patent No. 254,107, dated February 28, 1882.

Application filed October 10, 1881. (No model.)

To all whom it may concern:

Be it known that I, CLINTON BROWNING, a citizen of the United States, residing at Allegheny City, in the county of Allegheny and State of Pennsylvania, have invented a new and Improved Car-Coupling, of which the following is a specification.

My invention relates to a self-coupling for railroad-cars; and the nature of the same consists, first, in a pair of bifurcated or double-jawed draw-heads provided with shouldered laterally-swinging and interlocking levers, the draw-heads being constructed in such manner that while one of the jaws of the respective heads enters between the respective pairs of jaws, the jaws which do not enter extend along and clasp the outer sides of the jaws which do enter, and thereby prevent a casual lateral separation of the heads while the cars are turning curves, or under other circumstances, and the interlocking levers also being so constructed that they stand diagonal to the central line of draft, and their interlocking shoulders are at right angles, or nearly so, to the said diagonal line of the levers, and thus the strain upon the levers while the train is running is thrown in line with the pivots of the levers and taken entirely off the springs, which are only used to throw the levers into their locking positions and to keep the jaws coupled when the cars are not running, or when there is slack between the draw-heads, and besides this the jaws and levers are so formed that the draw-heads are allowed movements such as are secured by a knuckle-joint connection without being held against sufficient longitudinal movement when the cars are suddenly stopped or subjected to a back action; second, in the interlocking levers provided with shoulders which are continued from the top to the bottom of the draw-heads, in combination with the bifurcated or double-jawed draw-heads provided with depressions, one on the inner side of one jaw of each head, for the reception of the said continuation of the shoulders of the levers while the levers are being moved aside by the jaws in act of automatically coupling the cars; third, in the combination of hand-levers and locking-bars, springs, connecting-rods, shouldered interlock-

ing levers, and bifurcated or double-jawed draw-heads, whereby the draw-heads can be uncoupled from the platform, the interlocking levers can be automatically moved in position for automatically recoupling the draw-heads, 55 and when the draw-heads are coupled and under strain the springs will be relieved of such strain and the strain be thrown upon the pivots of the interlocking levers; fourth, in having the respective draw-heads united to their 60 spring draw-bars by means of a vertical pivot, whereby the draw-heads will move longitudinally with the draw-bars and at the same time have freedom to swing horizontally in turning curves; fifth, in providing the hinging-eyes of 65 the shouldered levers and jaws of the draw-head with rounded-off edges or corners, for the purpose of preventing the joints formed by these eyes being cramped by metal upset or displaced by the act of jamming the jaws 70 against one another to couple the cars; sixth, in draw-heads provided with interlocking levers which operate in a peculiar manner with respect to the line of draft of the cars.

In the accompanying drawings, which are 75 intended to illustrate my invention, Figure 1 is a side elevation, showing my invention as applied upon supports answering, by way of illustration, to such as are usually applied upon railroad-cars. In this view two draw-heads are 80 shown as coupled. Fig. 2 is a front elevation of one of the draw-heads, its adjuncts and supports answering, by way of illustration, to such as are provided on a car. Fig. 3 is a vertical section and partial elevation of one of the draw- 85 heads, spring draw-bars, interlocking levers, and supports of the draw head and bar. Fig. 4 is a plan view of Fig. 1, the end beam, locking-bar, and rail of one of the cars being removed and the same represented as in their positions by dotted lines. In this view the parts are adjusted to their uncoupling position and the draw-heads are shown as uncoupled. Fig. 5 is a detail view showing the interlocking levers in their coupling position, but uncoupled. 90 Fig. 6 shows the same as Fig. 5, except that the jaws are coupled. Fig. 7 is a detailed plan view of the draw-head, and Fig. 8 is a detail horizontal section of the interlocking lever. A is the front cross-beam of the platform of 100

a car-frame, B; C C', the end rails of the platform; D D', the sliding draw-bars, provided as usual with springs *a*, which serve to relieve the draw-heads H H' when bumping against each other. In the end rail C' of each of the car-platforms a long slot, *b*, is provided, having a locking-shoulder, *c*, and down through this slot a hand-lever, E, is passed, and after being pivoted at *d* to the front beam, A, is connected by its lower end to a laterally-moving rod, F, which is guided by a bracket, G, of the car-frame. This rod F has a head, *e*, with two jaws, *e' e'*, attached to its inner end, and between this head and the vertical portion *f* of the bracket G a spiral spring, F', is placed around the rod. The jaws of the rod loosely clasp the draw-head H, and they are perforated to receive a pivot, *g*, which connects the rod with the interlocking lever I of the draw-head, said lever being connected by a pivot, *h*, to the front end of one of the jaws of the draw-head. Both draw-heads H H', levers I I', and their adjuncts are constructed precisely alike; but the jaw H, carrying the interlocking lever I, stands on the right side of the center line of draft on one car and on the left side of said line on the other car; and the slotted locking-bar of the rail, the lever, and the rod and spring for operating the interlocking lever I of one car stand on the right-hand side of said line, while the interlocking-lever I', and parts for operating it, of the other car stand on the left-hand side of the said line.

The draw-heads H H' are loosely jointed to the spring draw-bars D D' by means of suitable fitting and vertical pivots, *i*, and they can swing on said pivots while the cars are turning curves. At their front ends the draw-bars are bifurcated or formed with two jaws, *k k'*. These jaws extend forward from a solid body portion of the draw-head, and at their rear end they are united on their inner sides by a semi-circle, or nearly a semicircle, and from this circle they inclose a gradually-widened oblong space, which on one side is bounded by a curved extension of the jaw *k* in form of a cyma reversa, and on the opposite side by a very obtuse angled extension of the jaw *k'*, as shown in Fig. 1 of the drawings. The exterior surfaces of the respective jaws partake very closely of the form of the interior surfaces thereof. In the jaw *k'* a depression or recess, *l*, having a beveled surface, *l'*, is formed, as shown, for a purpose presently described. At the extreme front end of the jaw *k'* nearly circular hinging ears or lugs *m* are formed, a space, *m²*, being between the same, and one lug being at the top and the other at the bottom of the jaw.

The interlocking lever I is bifurcated at its front and rear ends, and it is formed with a right-angled shoulder, *n*, between its bifurcated ends, as shown. This lever fits under and on top of the draw-head H, and its front ends are perforated to coincide with the holes in the front hinging ends of the draw-head, and through these perforated ends of the hinging-

ears of the draw-head the hinge pivot or pin *h* is passed for the purpose of hinging the lever to the draw-head. The shouldered portion *n* of the lever is curved or beveled at *n'* on its rear side, and is otherwise so shaped that it enters the recess *l*, and its front surface stands flush with the inner surface of the jaw *k'* when the lever I' is moved sidewise, as illustrated in the drawings, Fig. 4; but it extends out between the jaws some distance from the inner face of the jaw *k'* when either the lever I or I' is allowed to assume a coupling position, as shown in Figs. 5 and 6. By having the levers I I' bifurcated and formed with a long shoulder, *n*, extending from top to bottom of the draw-head great strength for sustaining the pulling-strain of the cars is secured.

In order to prevent cramping of the joint formed between the draw-heads and the interlocking levers by the upsetting of the metal when the draw-heads jam together, the corners *p* of the hinging ears or lugs are rounded off, as shown in the drawings. The pivots of the shouldered interlocking levers are set on opposite sides of the central line of draft, and by this arrangement the right-angled interlocking shoulders are caused by the action of their springs to stand diagonal to this line when the draw-heads are coupled and the pull or strain 95 comes diagonal to said line of draft, and is thrown directly and wholly upon the pivots of the levers; and by this action of the levers the springs are relieved of the pulling-strain of the cars, and they are therefore not depended upon for holding the draw-heads in their coupled position. The springs, however, act to prevent a separation of the draw-heads when there is slack motion or a back action of the draw-heads.

To couple cars with my improved coupling 105 the levers E are set free from the locking-shoulders *c* of the rail C', and the springs F' allowed to move the shouldered interlocking levers to the position shown in Fig. 5. Now, by bumping the draw-heads together, the hinged lever 110 of one draw-head will strike against the hinged lever of the other, and a mutual lateral displacement of the levers will take place until the shouldered portions of the levers coincide, when the shouldered part of one will be caused 115 to interlock with the shouldered part of the other by the spiral springs F'.

To uncouple the draw-heads move either the interlocking lever I or I' to a position corresponding to the position of the lever I in Fig. 120 4, and then separate the draw-heads by running either the one of two cars backward or forward.

By having hinging ends of the draw-heads 125 formed with spaces *m²* between their hanging lugs or ears *m* an ordinary link may be used between the draw-heads for coupling the cars, as occasion may require. When a link is used the pivots or pins *o* are raised sufficiently to admit the link between the lugs or ears *m* 130 into the spaces *m²*, and then lowered through the link and ears, upon which it rests. Thus

the pivots or pins h subserve two purposes—the one of fastening the levers and the other of holding a link-coupling.

Previous to my invention bifurcated draw-heads constructed so as to have one of the jaws on one head enter between two of the jaws on another head were well known; also, such draw-heads had been provided with coupling-tumblers, which were arranged to turn on pivots, for the purpose of insuring a frictional bind of one tumbler upon another while the cars are pulling against one another; but my invention obviates the necessity of depending alone upon the frictional contact of the coupling devices to insure the retention of the cars in a coupled condition, it providing positive interlocking or hooking shoulders in rear of the pivots of the coupling devices as a means for positively coupling the cars; also, lever-ex-

15 tensions on the coupling devices, whereby the cars can be readily uncoupled. It also affords very strong and long interlocking shoulders, and admits of an ordinary link being used in cases of necessity.

20 25 I do not wish to be understood as setting up a claim for anything shown in Reissue Letters Patent No. 9,727; but

What I claim as my invention, and desire to secure by Letters Patent, is—

30 1. The levers $I I'$, provided with flat or lateral hooking or interlocking shoulders n between their front and rear extensions, and with pivot-pin holes in their front extensions, in combination with the draw-heads $H H'$, formed 35 as described, and with the pivot-pins $h h$, substantially as and for the purpose described.

2. The levers $I I'$, provided respectively with a flat or laterally-extended shoulder, n , and a bevel, n' , and with two arms at their front and 40 two at their rear ends, and with pivot-pin holes in their front ends, and both levers united by

a body of metal, which forms also a shoulder from top to bottom of the respective draw-heads, in combination with the draw-heads formed respectively, as described, with a bifurcated end and with a depression, l , substantially as and for the purpose described.

3. The levers $I I'$, provided respectively with a flat or lateral shoulder, n , and upper and lower rear and front extensions, in combination with the bifurcated draw-heads $H H'$, rods F , springs F' , hand-levers E , and locking-bars C , substantially as and for the purpose described.

4. The combination of the bifurcated draw-heads $H H'$, levers $I I'$, provided with flat or lateral shoulders n , and the spring draw-bars $D D'$, connected to the draw-heads by vertical hinge-pivots i , substantially as and for the purpose described.

5. The hinging-ears m of the draw-heads $H H'$, having a space, m^2 , between them, and rounded at their corners p , in combination with the hinging ears or ends of the levers, $I I'$, and with the vertically-sliding or removable pivot-pins h , substantially as and for the purpose described.

6. The bifurcated draw-heads $H H'$, provided with interlocking levers which have flat or lateral interlocking shoulders n , and are pivoted as described, and are arranged and constructed to pull squarely against the respective flat shoulders n of one another on a line diagonal to a central line of draft of the cars, and thereby relieve the springs of the levers $I I'$ from strain while at the same time the draw-heads maintain their coupled position, substantially as described.

CLINTON BROWNING.
